UNITED STATES PATENT OFFICE.

LEWIS L. EVANS, OF BRIDGEPORT, CONNECTICUT, AND GERALD M. HART, OF WILKES-BARRE, PENNSYLVANIA.

SWITCH MECHANISM.

Application filed May 10, 1920. Serial No. 380,063.

To all whom it may concern:

Be it known that we, LEWIS L. EVANS, a citizen of the United States, residing at Bridgeport, county of Fairfield, State of Connecticut, and GERALD M. HART, a citizen of the United States, residing at Wilkes-Barre, county of Luzerne, State of Pennsylvania, have invented an Improvement in Switch Mechanism, of which the following 10 is a specification.

The object of the present invention is to provide improved electric switch mechanism which is simple and practical in construction and efficient and dependable in use.

15 With the above and other objects in view we have devised the novel mechanism which will now be fully described and will herein-after be specifically claimed.

20 In the accompanying drawing forming a part of this specification,

Fig. 1 is an elevation of a lamp socket of the lever type in which is incorporated the novel switch mechanism;

25 Fig. 2 a longitudinal, vertical section, on a greatly enlarged scale, of the socket of Fig. 1;

Fig. 3 a section on line 3—3 in Fig. 2, looking in the direction of the arrows;

30 Fig. 4, a section on line 4—4 in Fig. 2, looking in the direction of the arrows;

Fig. 5, an elevation of a lamp socket of the pull type, a part being broken away to show the manner of incorporating the improved mechanism; and

35 Fig. 6 is a perspective view of the contact wheel and its associated parts.

10 denotes a switch shell, and 11 denotes insulation. Our novel switch mechanism is carried by an upper insulating block 12 and 40 a lower insulating block 13 which are incorporated in the switch shell. The insulating blocks are held in proper positions with respect to each other by a supporting post 14 and by binding posts 15 and 16 which carry 45 binding screws 17 and 18, respectively. A screw shell 19 is supported by the lower insulating block in usual manner and has contact with binding post 15 by means of screw 20 which passes through the lower insulating block and engages both the screw shell and binding post 15, as more clearly shown in Fig. 4. As disclosed in Fig. 2, the upper insulating block is centrally apertured as indicated at 21 and the lower insulating block

is also centrally apertured to receive a metal 55 bushing 22 which is itself provided with an opening designated 23. The center contact, denoted by 24, is carried by metal bushing 22, and a shaft 25 on which are located the contact wheel and associated parts has bearings in the aperture in the upper insulating block and in opening 23 in bushing 22. The shaft is rotatably arranged in its bearings and fixedly carries the contact wheel and its 60 associated parts.

65 The contact wheel, as clearly disclosed in Figs. 2, 3, 4, and 6, consists of insulating material, denoted by 26, and rotary contacts of metal denoted by 27. The rotary contacts are arc shaped arms which are arranged at diametrically opposite points in the outer portion of the contact wheel, as shown, and extend in opposite directions from a connecting strip 29 on shaft 25. The shaft thus comprises the core of the rotary 70 contacts. The contact wheel, including the insulating material and rotary contacts, has its outer portion beveled to V shape, as indicated by 30, and the portions of the insulating material and of the rotary contacts of 75 metal which lie in the perimeter of the wheel are flush with each other. That is, the outer portion of the wheel provides a smooth and even surface. It will be apparent that the connecting strip, designated 29, may be 80 of the thickness of the wheel, or of less thickness. When of less thickness, its upper and lower surfaces will be covered by the insulating material of the wheel. A spring 85 arm bracket 31 attached to binding post 16 carries a fixed contact member or pulley 32. The spring arm bracket is provided with 90 attaching ears 33 between which the pulley is positioned. A pin 34 passing through the center of the pulley and through the ears rotatably supports the fixed contact member or pulley. The pulley is arranged at a proper 95 position on binding post 16 so that it may engage the V-shaped portion of the contact wheel, and as more clearly shown in Fig. 2, 100 the perimeter of the fixed contact member or pulley is of such shape as to fit snugly against said V-shaped portion, as will be readily understood.

105 The contact wheel carries an upper ratchet 35 and a lower ratchet 36, which are preferably composed of insulating material. As clearly disclosed in Figs. 2 and 6, the

ratchets are spaced from the contact wheel by disk shaped shoulders 55. The shoulders can, however, be dispensed with. As shown, the contact wheel, the disk shaped shoulders and the ratchets are preferably moulded about the rotary contacts and form a balanced unit. The upper ratchet affords a ready means for actuating the contact wheel. As shown in Figs. 1 to 4, inclusive, 10 an operating lever 37 has an enlarged portion 38 with an opening 39 through which shaft 25 freely passes. A coil spring 40 arranged on the shaft has one of its ends secured to the upper insulating block, as indicated at 41, and its other end secured to the operating lever, as indicated at 42. A flat spring 43 secured to the underside of the operating lever has its outer end 44 arranged so that it will engage the shoulders, 20 denoted by 45, of upper ratchet 35. A suitable slot 46, is provided in the switch shell for throwing the operating lever. The switch mechanism of Fig. 5 is in all respects similar to that of the other figures. 25 A quadrant 47 rotatably mounted on shaft 25 is provided with a pull chain or cord 48 which freely passes through an opening 49 in the switch shell. The quadrant carries a flat spring 43 which is arranged to engage 30 the shoulders of the upper ratchet as in the case of the similar spring of the other figures. It will be apparent that when the operating lever is moved from its dotted line position in Fig. 3 to its full line position in said figure, the flat spring, by reason 35 of its engagement with a shoulder 45 on the upper ratchet, will cause the contact wheel to make a quarter turn. When the operating lever is released, it will be returned by 40 the coil spring in a well known manner to the dotted line position, the outer portion of spring 43 riding up over the cam surface, denoted by 50, of the upper ratchet and positioning itself back of a shoulder 45, as 45 will be readily understood.

A flat spring 51 is secured in proper position on supporting post 14, as indicated at 52, so that its outer portion 53 may spring back of one of the shoulders, denoted by 54, 50 on the lower ratchet at the end of each actuation of the operating lever and consequent quarter turn of the contact wheel. As has been described, the rotary contacts are at diametrically opposite sides of the contact wheel. When the contact wheel is in the position shown in the drawing, that is, when the fixed contact pulley is in engagement with one of the rotary contacts, the circuit is closed. The current passes 55 through binding screw 18, binding post 16, spring arm bracket 31, fixed contact member or pulley 32, one of the rotary contacts, connecting strip 29, shaft 25, metal bushing 22, center contact 24, through the lamp, and 60 through screw shell 19, binding post 15 and

binding screw 17. When now the contact wheel is given a quarter turn, either by the operating lever of Figs. 1 to 4, inclusive, or by the pull chain or cord of Fig. 5, the fixed contact member or pulley will be out of engagement with a rotary contact, but will bear against a portion of the insulating material of the contact wheel. The circuit will consequently be opened.

The shoulders on the upper and lower 75 ratchets are arranged with respect to each other so that the position of the contact wheel with respect to the fixed contact member or pulley is insured. That is, when the switch is in "on" position, one of the rotary 80 contacts engages the fixed contact member or pulley, and when in "off" position, the rotary contacts are separated from the contact pulley, the insulating material of the contact wheel and the contact pulley then engaging each other. The shoulders of the lower ratchet are beveled in suitable manner, to cause flat spring 51 to pass back of each shoulder of the lower ratchet with a 85 snap.

It will be evident that the arrangement of rotary contacts and contact pulley as hereinbefore fully described affords an especially durable switch mechanism for the reason that there is a rolling connection between 90 said rotary contacts and pulley.

While a specific embodiment of the invention has been described, it is to be here understood that such changes in details of construction and arrangement of parts may 100 be made as fall within the spirit of the invention and within the scope of the appended claims. For example, any convenient means may be employed for actuating the upper ratchet, a plurality of fixed contact 105 pulleys may be employed, or flat spring 51 may be supported by one of the binding posts.

Having thus fully described our invention, we claim:

1. In a switch mechanism, a rotatable contact wheel the perimeter of which includes contacts and insulating material separating the contacts, insulating blocks supporting the rotatable contact wheel, upper and lower ratchets carried by the contact wheel, means for actuating the upper ratchet, co-operating means engaging the lower ratchet whereby the proper position of the contact wheel is insured, and a rotatable contact 115 member having rolling connection with the contact wheel and adapted to alternately engage said contacts and insulating material.

2. In a switch mechanism, a rotatable contact wheel the perimeter of which includes contacts and insulating material separating the contacts, insulating blocks supporting the rotatable contact wheel, upper and lower ratchets integrally carried by the contact wheel, means for actuating the upper ratchet 125 120

125

and cooperating means engaging the lower ratchet in such manner that the proper position of the contact wheel is insured.

3. In a switch mechanism, a rotatable contact wheel the perimeter of which is spaced at uniform distance from the wheel center and includes contacts and insulating material spacing the contacts from each other, a rotatable contact member bearing against 10 the perimeter of the contact wheel and adapted to alternately engage and have rolling connection with the contacts and insu-

lating material, upper and lower ratchets upon said contact wheel, means associated with said upper ratchet for actuating said contact wheel, and a stop cooperating with said lower ratchet for insuring that the contact wheel will remain in any position to which rotated.

In testimony whereof we hereunto affix ~~so~~ our signatures.

LEWIS L. EVANS,
GERALD M. HART.
